UNITED STATES PATENT OFFICE.

KALMAN F. BENKO, OF SYRACUSE, NEW YORK.

WINDOW-SCREEN.

1,184,305.

Specification of Letters Patent.

Patented May 23, 1916.

Application filed August 30, 1915. Serial No. 48,020.

To all whom it may concern:

Be it known that I, KALMAN F. BENKO, a citizen of the United States of America, and resident of Syracuse, in the county of 5 Onondaga, in the State of New York, have invented new and useful Improvements in Window-Screens, of which the following, taken in connection with the accompanying drawings, is a full, clear, and exact description.

This invention relates to certain improvements in window screens of the roller curtain type, and refers more particularly to the means for supporting and operating the 15 screen.

It is proposed to use fine wire or cloth screen specially treated to render it weather-proof, either of which would be more or less stiff and difficult to wind upon rollers of 20 relatively small diameter, and one of the main objects of my present invention is to enable such screens to be wound more or less compactly upon such rollers.

Another object is to maintain the screen 25 in a substantially flat plane against buckling when adjusted for use, and also to prevent stretching of the edges thereof.

Other objects relating to specific parts of the screen and its supporting and operating 30 means will be brought out in the following description.

In the drawings, Figure 1 is a front elevation, partly in section, of a window screen embodying the various features of my invention and window frame in which it is mounted. Fig. 2 is a transverse vertical sectional view through the same window frame and screen, taken on line 2-2, Fig. 1. Fig. 3 is an enlarged horizontal sectional view, 35 partly broken away, and taken on line 3-3, Fig. 1. Fig. 4 is an enlarged front elevation, partly broken away, of the lower right-hand corner of the screen, showing more particularly the manner of applying the 40 binding strips and operating tapes. Figs. 5 and 6 are detail sectional views, taken, respectively, on lines 5-5, and 6-6, Fig. 4. Fig. 7 is a sectional view taken on line 7-7, Fig. 1. Fig. 8 is a front elevation, partly 45 broken away and partly in section, of a window frame and screen, showing a slightly modified form of operating means in which the curtain is drawn upwardly from the bottom instead of downwardly from the top,

as shown in the previous figures. Fig. 9 is 55 an enlarged transverse sectional view through one of the guides for the adjacent edge of the screen shown in Fig. 8.

As illustrated in Figs. 1 to 7, inclusive, the operating means for the screen as —1— 60 is built into the frame A of the window in such manner as to permit the screen to be adjusted vertically from the top downwardly across the outside of the window and in close proximity to the outermost sash, 65 and comprises an upper roller —2— and a lower roller —3— located, respectively, in suitable housings in the top and bottom portions of the frame A above and below the window sash.

The upper roller —2— is adapted to be 70 driven in one direction for winding the screen —1— thereon by means of a spring motor —4— through the medium of intermeshing sets of gears —5— and —6— of 75 such ratio as to impart a relatively greater speed of rotation to the roller —2— than that of the motor shaft.

The lower roller —3— is adapted to be 80 operated by hand for drawing the curtain down across the window opening against the action of the retracting spring —4—, and for this purpose is provided with end sheaves —7— and a central or intermediate sheave —8—, the end sheaves —7— being 85 connected by tapes —9— to the lower end of the screen in a manner hereinafter described, while the intermediate sheave —8— is connected to one end of a pull cable or tape —10— extending outwardly through an 90 opening —11— in the inner side of the lower housing and is provided with apertures —12— for engaging with a suitable catch —13— also on the inner face of the housing so that the cable may be operated from the 95 room to which the window leads.

The screen —1— is of sufficient size and area to cover the window opening and is preferably made of fine mesh, flexible copper wire or equivalent material, except that its 100 upper end consists of a relatively short length of more flexible cloth webbing or cloth screen —1'— which is attached at its upper end directly to the upper cylindrical roller —2—, while its lower end is attached 105 by a flexible binding tape —14— (Fig. 7), to the upper end of the woven wire screen —1—.

The object in connecting the upper end of the screen —1— to the re-winding roller —2— by means of a more flexible cloth webbing —1'— and attaching the cloth webbing —1'— to the upper end of the screen by means of a flexible tape in the manner shown is to prevent buckling of the wire screen upon the roller during its initial winding thereon, and also to permit the wire screen to be wound smoothly and compactly upon a re-winding roller of relatively small diameter.

It will be observed upon reference to Fig. 3 that the screen —1— extends from side to side of and between the sides of the window frame, the opposite upright edges thereof being guided in vertical channels —15— in the outer sash stops and are covered and protected by tape openings —16— stitched or otherwise secured thereto and running the entire length of the screen to prevent stretching of the edges of the wire fabric and also to enable such fabric to be wound and unwound upon and from the roller —2— with greater uniformity and smoothness, said binding strips also serving to protect the edges of the wire against undue wear in traveling along the ways or channels —15—.

The lower edge of the screen is firmly clamped between a pair of reinforcing bars —17— of wood or equivalent stiff material, as shown more clearly in Figs. 4 and 5, said bars being co-extensive in length with the distance between the stops and channels —15— and constituting a stiffening bar for retaining this portion of the screen in a substantially flat plane and is adapted to lie closely against the upper face of the window sill when the screen is drawn to the limit of its downward movement, thus serving to exclude flies and other insects.

The inner section of the bar is somewhat thicker than the outer section so that its inner face may travel in a vertical plane close to that of the outer face of the outermost sash, so that if the outer sash is lowered for ventilation while the inner sash is closed, the inner face of the bar —17— may be lowered into registration with the outer face of the outermost rail of the outer sash and locked in such position against the action of the retracting spring —4— by engagement of the pull strap —10— with the catch —13—, or if the inner sash is elevated, the screen may be drawn to the limit of its downward movement with the bar —17— resting against the window sill and held in such position by the same strap and catch.

The remaining portions of the screen —1— are retained in a substantially flat plane by means of additional stiffening bars —18— of thin sheet metal or equivalent material secured at intervals to the outer face of the screen transversely thereof and in parallelism with the lower bar —17—, the

stiffening bars —18— being relatively narrow so as to roll easily with the screen upon the roller —2—.

In order that the strain of the straps —9— may be transmitted to the entire lower edge of the screen, the upper ends thereof are attached directly to apertured metal extensions or plates —20— which in turn are rigidly secured to and between the opposite ends of the bars —17—, as shown more clearly in Figs. 4 and 5, and extend outwardly beyond the edges of the screen to ride in the grooves or channels —15—, said plates being provided with slots —21— in vertical alignment with binding strips —16— for receiving the adjacent ends of the tapes —9—, the lower ends of said tapes being attached to their respective sheaves —7—. It, therefore, follows that the tapes —9— are in vertical alignment with the binding strips —16— and any pull upon the tapes —9— will be transmitted to the bars —17— through the medium of the plates —20—, thus preventing stretching of the edges of the screen.

The screen and its operating means shown in Fig. 8 is adapted to be applied to window frames of buildings after completion, and although I have shown the re-winding roller at the bottom and the adjusting roller at the top, this order may be reversed if desired. As shown, however, the re-winding roller is mounted in a separate housing —24— adapted to rest upon the sill or stool of the window, but otherwise is substantially the same as that shown in Fig. 1. The screen as —1— is, in this instance, made entirely of cloth of relatively fine mesh, shellacked or otherwise treated, to render it weather-proof without materially diminishing its flexibility, one end of the screen being attached directly to the roller —2—, while its upper end is attached to a stiffening bar —17— similar to that previously described, except that the end plates —20— are omitted. The central portion of the bar —17— is attached to one end of a pull cord or cable —10'— which is passed over a roller or sheave —25— centrally on the head or top of the window frame, leaving the opposite end free to be operated by hand from the room to which the window leads.

Secured to the upright side of the window frame are suitable ways —15'— in which the tape-bound edges of the screen —1— ride as the screen is raised and lowered against or with the action of the spring motor —4—.

The operation of my invention will now be readily understood upon reference to the foregoing description and the accompanying drawings.

What I claim is:

1. In combination with a window frame having upright ways at opposite sides of

- the window opening, rollers mounted on the frame above and below said opening, a screen curtain movable vertically in said ways and having one end attached to 5 one of the rollers, connections between the other end of the curtain and the other roller, means for operating the last-named roller to unwind the curtain from the first-named roller, and retracting means for said first-named roller to re-wind the curtain thereon.
2. In combination with a window frame having upright ways at opposite sides of the window opening, rollers mounted on the frame above and below said opening, a screen 15 curtain movable vertically in said ways and having one end attached to one of the rollers, connections between the free end of the curtain and the other roller, means for rotating the last-named roller to adjust the 20 curtain from the first-named roller, and retracting means for said first-named roller.
3. In combination with a window frame having upright ways at opposite sides of the window opening, rollers mounted on the 25 frame above and below said opening, a screen curtain movable vertically in said ways and having one end attached to one of the rollers, a cross bar secured to the free end of the curtain to hold the latter in a substantially flat plane against buckling, motor-driven means for operating one of the rollers to re-wind the curtain thereon, connections between said cross bar and the other roller for adjusting the curtain against the 30 action of its re-winding means, and means for rotating the last-named roller.
4. In combination with a window frame, a spring-retracted roller above the opening in the frame, a separate roller below said 40 opening, a screen curtain attached to the upper roller, a cross bar secured to the lower end of the curtain to hold it against buckling, strap connections between the ends of said cross bar and the lower roller for ad-
- justing the curtain against the action of the 45 retracting spring, and means for rotating the lower roller.
5. In combination with a window frame having upright guide ways at opposite sides of the window opening, a spring-retracted 50 roller mounted on the frame above the opening, a separate roller mounted on the frame below the opening, a screen curtain having its upper end attached to the upper roller to be wound and unwound thereon and 55 therefrom, binding strips secured to opposite upright edges of the curtain and movable in said ways to protect such edges against stretching and undue wear, a cross bar secured to the lower edge of the curtain and 60 provided with end plates projecting beyond the adjacent binding strips, flexible connections between said plates and the lower roller in approximate alinement with the binding strips, and means operable at will 65 for rotating said lower roller.
6. In combination with a window frame, a roller above the opening in the frame, a separate roller below said opening, a screen curtain having a main body of wire fabric 70 of sufficient area to cover said opening and a relatively short cloth fabric connected thereto and to the upper roller to cause the wire screen to roll more smoothly upon the roller, a cross bar attached to the lower end 75 of the wire screen, connections between the opposite ends of the cross bar and lower roller, means operable at will for rotating the lower roller, and spring-retracted means for the upper roller for re-winding the curtain thereon.

In witness whereof I have hereunto set my hand this thirteenth day of August, 1915.

KALMAN F. BENKO.
